UNITED STATES PATENT OFFICE.

GEORGE ANDERSON, OF WEYERHAUSER, WISCONSIN.

CURTAIN-ROD AND SHADE-ROLLER HANGER.

1,303,812.

Specification of Letters Patent. Patented May 13, 1919.

Application filed January 31, 1917. Serial No. 145,704.

To all whom it may concern:

Be it known that I, GEORGE ANDERSON, a citizen of the United States, and a resident of Weyerhauser, in the county of Rusk and State of Wisconsin, have invented a certain new and useful Improvement in Curtain-Rod and Shade-Roller Hangers, of which the following is a specification.

The present invention relates to curtain rod and shade roller hangers, and particularly to that type for application to the casings of windows and the like.

An object of the present invention is to provide a hanger of this character which 15 comprises but relatively few parts capable of quick and easy assembly and which may be readily applied to the window casings and clamped securely in such position without the use of screws, nails, or other like fastening devices.

The invention further aims at the provision of a hanger of this nature which is provided with a pair of opposed members adapted to be drawn toward each other for clamping against the opposite sides of a window casing, and which has each member peculiarly formed from a body or bracket plate made from a single blank which is so stamped and bent as to provide the window engaging means, the bracket arm for supporting the curtain rod, and a support for adjustably holding the shade roller engaging parts.

A still further object of the present invention is to provide an improved clamping and locking means for the opposed parts of the hanger to firmly bind the same against the opposite sides of the window casing, and to securely lock the parts in such position that the hanger is capable of withstanding considerable pressure.

The present invention also aims at the provision of a hanger embodying the above features, and which is entirely constructed 45 from sheet metal which may be stamped and bent into the desired form to provide the relatively few elements which make up the device.

The above, and other objects and advantages of this invention will be more particularly brought out in the following detailed description of the present preferred embodiment, the same being illustrated in the accompanying drawings wherein:

55 Figure 1 is a perspective view of the complete hanger, the intermediate portion there-

of being broken away, and the same being disclosed as in applied position.

Fig. 2 is a plan view of the blank of the bracket or body plate of one of the hanger members.

Fig. 3 is a detail perspective view, enlarged, of one of the shade roller engaging arms or supports.

Fig. 4 is a detail perspective view of the 65 telescoping sleeve and bar for holding the hanger parts together, the sleeve and bar being shown separated, and the locking and clamping lever being also shown in position upon the sleeve.

Fig. 5 is a longitudinal section taken 70 through the same assembled, and in clamped position.

Referring to this drawing, wherein like parts are designated by similar numerals of 75 reference throughout the several views, the hanger comprises a pair of members which are similarly formed, and which are identical in construction with the exception that the parts thereof are extended in opposite 80 directions so as to project inwardly of the window casing when applied to the opposite sides of the same.

Each member comprises a body or bracket plate 10 formed of a single blank which is 85 suitably stamped into substantially rectangular form and provided upon its rear edge with a longitudinal row of teeth 11 adapted to be bent at right angles to the plane of the plate 10, and inwardly of the same for biting 90 engagement against the adjacent side of the window casing. The blank or plate 10 is provided at its upper edge with an upwardly extending and forwardly inclined arm 12 adapted to support upon its upper end the 95 adjacent extremity of a curtain rod 13, and for this purpose is provided with a recess or pocket 14 in its upper extremity for the reception of curtain rods.

The plate 10 is provided, as an integral 100 part thereof, with a lug or ear 15 projecting from the forward edge of the plate and adapted to be bent inwardly therefrom. The lug 15 is relatively long and substantially rectangular in form, and has its upper 105 and lower edges rolled over rearwardly to provide guiding flanges 16 adapted to slidably hold the flat shank 17 of the shade roller supporting arm 18, against the rear face of the ear 15. The body plate 10 is also 110 provided at its middle portion, with a preferably elongated vertically extending aper-

ture 19 through which may be secured one element of a clamping and locking means which will be hereinafter set forth.

In Fig. 3 there is shown in detail the shade roller supporting arm 18 and its integral shank 17, the two parts being preferably formed from a single piece of metal which is stamped to the desired configuration, and bent as shown. It is of course understood that the outer end of the arm 18 may have its aperture or socket formed to receive either end of the shade roller.

One form of clamping and locking means for the opposed members of the hanger is disclosed in Figs. 1, 4 and 5 of the drawing. In this form, a relatively flat sheet metal tube 20 is swaged or riveted at its outer end through the opening 19 of the adjacent bracket plate 10, and is adapted to slidably receive in its opposite end a sheet metal bar 21 which is swaged or riveted at its outer end through the opening 19 of the opposite bracket plate.

The inner free end of the tube 20 is provided with a projecting lip 22 at its inner side adapted to bear against the rear side of the bar 21. A pair of vertically aligned lugs 23 project outwardly from the top and bottom edges of the tube 20 directly opposite to the lip 22. A combined clamping and locking lever 24 is pivoted, as at 25, between the lugs 23 and has its engaging end or nose 26 projecting at an obtuse angle from the body portion or handle of the lever 24. The lever 24, when locked, is adapted to lie against the outer face of the bar 21. The bar 21 is provided upon its inner end with a longitudinal row of notches or recesses 27 adapted to receive, one at a time, the nose 26 of the lever 24. To introduce the inner end of the bar 21 into the tube 20, the lever 24 must be swung into the dotted-line position shown in Fig. 5. As soon as the bar 21 is in adjusted position, the lever 24 is swung over into its full-line position and the nose 26 thereof engages in the adjacent notch or recess 27. The free end of the nose 26 is preferably flattened as shown and is adapted to bear against the inner wall of the recess 27 and thus bind the lever 24 from turning upon its pivot 25 to hold the parts of the clamping means from separation. As the handle or body portion of the lever 24 is relatively long, it will be readily understood that considerable pressure may be brought to bear upon the nose 26 for the purpose of drawing the bar 21 into the tube 20 and thus clamp the opposed members of the hanger against the opposite sides of the window casing.

When the opposed members of the hanger are engaged against the opposite sides of a window casing, and the combined clamping and locking means is operated, the opposed bracket plates 10 are drawn toward each other and the teeth 11 thereof are caused to bite into the sides of the window casing to thus support the hanger rigidly in position thereon. As the clamping and locking means is secured to the middle portion of the bracket plate 10, the teeth 11 are spaced sufficiently rearwardly to obtain the desired grip upon the window casing, and the pressure exerted by the binding means is substantially direct upon the teeth.

It will be noted that practically all parts of the device may be stamped from sheet metal, that the device comprises but relatively few parts, and that it may be packed for shipment in a relatively small space.

The curtain pole 13 may be made of two or more parts telescopically connected so that the curtain pole may be adjusted to windows of various widths and be conveniently supported upon the upper ends of the bracket arms 12. The ears 15 are provided with openings 33 therethrough adapted to register with openings 34 formed through the shanks 17 of the shade roller supporting arms. Screws 35, or the like, may be passed through the openings 33 and 34 and brought into register to detachably hold the shanks 17 upon the brackets.

It is of course understood that various changes and modifications may be made in the above-specifically described construction without departing from the spirit of the invention, the changes and modifications being restricted only by the scope of the following claim.

I claim:—

A shade and curtain rod support comprising a pair of plates having means to engage the sides of a window frame, and means for clamping said plates in adjusted positions on the window frame comprising a flattened tube secured to one plate and carrying a clamping lever at its extremity opposite of said plate, and a bar secured to the other plate in telescopic relation to said flattened tube having a series of transverse slots, said lever having a nose extending at a slight angle to the lever to engage in said slots and force the bar into said tube, said lever adapted to lie in longitudinal engagement with said bar to hold said nose in engagement with a side of one of said slots to lock the tube and bar in adjusted position.

GEORGE ANDERSON.
